UNITED STATES PATENT OFFICE.

SIDNEY C. VINCENT, OF BALTIMORE, MARYLAND.

TOY CLOCK.

Application filed November 11, 1925 Serial No. 68,384.

This invention relates to a toy clock, intended entirely for the amusement of children. The first object is to so simplify the construction as to render it possible to manufacture the toy at an insignificant cost, so that it may be sold cheaply in such place, for instance, as five and ten cent stores, and at the same time, be of such attractive character to children as to give them amusement to an extent greatly out of proportion to the cost of the article.

The invention contemplates a construction in which all the parts can be made by simple stamping operations, and to so form the casing that it may be readily and cheaply assembled, and to make the internal parts few in number, and at the same time cheap, and of such form that they will cooperate with the case in assembling in the quickest and cheapest possible manner, at the same time produce a device that operates perfectly for the purpose for which it is intended.

In the drawings, Figure 1 is a face view of the clock with the upper portion of the front part of the casing broken away, and the bell in section.

Figure 2 is a perspective view of the back section of the casing.

Figure 3 is a perspective view of the front part of the casing looking at its inside thereof.

Figure 4 is a perspective view of the operating crank.

Figure 5 is a vertical section.

Figure 6 is a detail, showing the manner of attaching the front section of the casing to the rear section.

The case is made in two sections, stamped from single pieces of metal, a front section 1 and a back section 2. Each section is cup-shaped, and on the front plate of the front section is provided clock-face markings, from 1 to 12, and preferably adjacent each number, and arranged in circular fashion around the face, are representations of animals and birds. These, however, may be replaced by pictures of other objects of a kind that would appeal to children.

The front section is provided with a central perforation 3 for the passage of the stub of the crank member, which will be presently described. The flange of the front section is cut away at its top as indicated at 5 to provide a recess which permits the oscillation or vibration of the bell-clapper. This flange is further cut away as indicated at 6 and the cut

portions are bent down to form feet 7, which in conjunction with the lower edge of the back section, serve to support the clock in upright position.

Pivoted at 8 in the lower part of the front section of the casing is the bell-clapper 9 which is formed of a single piece of metal shaped at its upper end to form the striker 10. The bell-clapper body is formed with a contact point 11 and adjacent to this is a vertical recess 12. Co-operating with this contact point and recess, is the flat portion 13 of the crank member 14. The flattened portion of the crank member has integral therewith a short reduced portion 13', which extends through and has a bearing in the aperture 14' in the back section 2 of the casing. The crank member is formed of a single piece of metal and is provided at one end with a short stub 15, which extends through the perforation 3 in the front section. To this stub the hands 16 are attached. The crank portion is so bent as to form the crank handle 17, engaged by the hand to rotate the crank member.

In operation when the parts are assembled, the edges of the flattened portion 13 alternately engage the part 11 and the edge *a* of the bell-clapper which will cause the clapper to oscillate with a rapidity according to the rapidity with which the crank is turned. The bell-clapper is cut away as indicated at 18 to clear the edge of the flattened portion 13 of the crank member 14.

The crank is rotated toward the person operating the toy and when one edge of the part 13 engages the part 11 it will throw the bell-clapper in the direction of the arrow in Figure 5, and when said part engages the surface *a*, the bell-clapper will be operated in the opposite direction, and so on.

It will be noted that the bell-clapper body is cut away in such a manner that the crank can be turned one way only, so that the hands 16 will turn in "clockwise" direction.

Supported on a stub 19 on the rear section of the casing is a bell 20, which is engaged by the striker 10 when the bell-clapper is oscillated.

The flange of the back section of the casing is formed with an annular groove 21 which receives the short extending laterally flange of the opposite section. When the two sections are together, by a simple spinning operation a part of the metal of the back section is spun down over the flange, thus firmly se-

curing the two sections of the casing together.

Claims—

1. A toy clock comprising a casing formed ⁵ of two cup-shape sections, a bell-clapper formed of a single piece of metal and pivoted at its lower end to one of the sections, a crank member supported in said sections and having hand-attaching means at one end, and ¹⁰ having its other end bent to form an exterior crank handle, said crank member being formed within the casing with a plate like flattened portion, whose edges are adapted to engage alternately and directly, portions ¹⁵ of the bell-clapper to cause the same to be oscillated when the crank is turned.
2. A toy clock comprising front and rear cup-shape portions constituting a casing, a

bell-clapper formed of a single piece of metal and pivoted at its lower end to the front section, said bell-clapper being formed with a head adapted to engage a bell, and also with portions adapted to be engaged by a portion of a crank member, said crank member being supported in the front and rear sections and having hand-attaching means at one end, and having its other end bent to form an exterior crank handle, said crank member being formed within the casing with an intermediate plate whose opposite edges are adapted ²⁵ to directly and alternately engage said portions of the bell-clapper to oscillate the same when the crank handle is rotated.

In testimony whereof he affixes his signature.

SIDNEY C. VINCENT.
